UNITED STATES PATENT OFFICE.

JOHN WEST, OF BROOKLYN, NEW YORK.

DESIGN FOR TYPE.

SPECIFICATION forming part of Design No. 15,645, dated December 23, 1884.

Application filed May 27, 1884. Term of patent 14 years.

To all whom it may concern:

Be it known that I, JOHN WEST, of Brooklyn, in the county of Kings and State of New York, have invented and produced a new and original Design for a Font of Type, of which the following is a specification.

Reference is to be had to the accompanying photograph, forming a part of this specification, and showing my newly-designed font of type.

The design consists in the concave ends of the heavy lines of the letters, which intersect and project beyond the light lines.

I claim—

The design for a font of type herein shown and described, consisting of the gradual swell from the center toward the ends in the straight lines of the letters, the terminal peaks not extending above the letters, and the concave ends of the heavy lines, which intersect and project beyond the light lines, as set forth.

JOHN WEST.
